4 Claims. (Cl. 242—55)

This invention relates to a method of and means for controlling the power drive in a winding or other machine, and has for its main object and feature the regulation of the amount of power to be supplied to said machine under different operating conditions thereof.

This application is a division of one filed September 10, 1937, Ser. No. 163,190.

In the accompanying drawings the invention is disclosed in a concrete and preferred form in which—

Fig. 1 is a side elevation of the machine looking in the direction of arrow 1 of Fig. 3;

Fig. 2 is a fragmentary section on the line 15 2—2, Fig. 1;

Fig. 3 is a top plan view of the same, parts being broken away and parts shown in section;

Fig. 4 is a side elevation of an upper fragmentary portion of Fig. 1 taken from the opposite 20 side of the machine;

Fig. 5 is a longitudinal vertical section of the machine on the line 5—5, Fig. 3;

Fig. 6 is an enlarged vertical section on the line 6—6 of Fig. 3, showing the slip friction 25 clutch whereby increased power is applied to the tapes at the beginning of each winding operation;

Fig. 7 is a fragmentary front elevation of the machine showing the power-controlling devices;

Fig. 8 is an enlarged front elevation of the 30 lower left-hand portion of Fig. 7, with the controls in changed positions; and

Fig. 9 is a view similar to Fig. 8, showing the controls in other positions.

Referring to the drawings, it will be seen that 35 Fig. 1 shows a roll or web of material 25 which passes over a power-driven roller 26 to a spreader 27. As shown in Fig. 5, said web passes from spreader 27 to and over a guide roller 28 and from thence under a slitter drum 29 between 40 which and a transverse series of cutters 30, the web is slitted longitudinally to form a multiplicity of strips or tapes. As the strips or tapes pass upwardly with their contiguous lateral edges in juxtaposition, alternate strips or tapes are di- 45 vided over a lower guide roller 31 to a lower spooling mechanism to be hereinafter described while the remaining strips or tapes continue their movement upwardly about an upper guide roller 32 to an upper spooling mechanism. In this way 50 the strips or tapes are formed into separate groups of laterally-spaced tapes arranged in a predetermined order in which they are to be separately spooled.

The upper and lower spooling mechanisms are 55 substantially similar in construction so that a

description of the upper one will serve for both. Journaled in opposite side frames 33 and 34 is a transverse head 35, said head being provided at one end with a shaft or journal 36 (Fig. 3) which extends through and projects beyond side frame 33. Mounted at the outer end of shaft 36 is a lever 37 whereby the head and spool supports are shifted through arcs of 180 degrees after each spooling operation. Keyed to shaft 36 at the outer surface of side frame 33 is a locking disk 38 which, as shown in Fig. 4, is provided with diametrically opposite notches 39 for receiving a spring-pressed bolt or detent 40 in a housing 41 mounted on the side frame, the head being thereby locked in a stationary position after each 5 rotational shift. Oppositely presented cutter blades 42 are suitably arranged on the head for severing the tapes or strips between the filled and empty spools in the manner described in parent application Ser. No. 163,190. Rigidly connected 10 to head 35 at opposite ends within side frames 33 and 34 are bearing frames or spiders 43 which carry fixed bearing members 44 and removable bearing caps 45 for journaling the spool-supporting arbors 48, said bearing caps being pivotally 15 mounted on spider frames 43, under the constraint of toggles 46 which are stabilized in either 20 position of the cap bearings by means of tension springs 47.

Suitable means for supplying power to the 30 machine, may be provided by a belt-driven pulley 76 (Figs. 1, 3 and 7) constructed and arranged to transmit power intermittently through a clutch 76a to a spur pinion 77. An axial thrust cam 78 for actuating said clutch may be operated by 35 a sprocket 79 over which a chain 80 is movable by a treadle 81. A gear 82 is driven by pinion 77, said gear being keyed to a transverse shaft 83 upon which drum 29 of the web-slitting device is mounted. Keyed to shaft 83 on the opposite 40 side of the machine, is a power-distributing gear 84 which meshes with a gear 85 (Figs. 1, 3 and 5). A driving sprocket 86 which is driven by 45 spur gear 85 is connected by a chain 87 to a follower sprocket 88. A friction coupling 89 (Fig. 2) is interposed between sprocket 88 and roller 26 (Fig. 1). A spur gear 90 (Figs. 1 and 6), driven by spur gear 84, transmits power through a slip friction clutch 91 to a spur gear 92. A small pinion 93 (Fig. 1) which is driven by gear 92, is 50 keyed to a spindle 94 journaled in side frame 34, a spur pinion 95 being also keyed to spindle 94 on the inner side of said frame for driving the upper spooling mechanism. A similar train of 55 gears comprising gear 96, slip friction clutch 97 98

(Fig. 3), gear 98, and gear 99, connects power distributing gear 84 to a pinion 100 for driving the lower spooling mechanism. Driving pinions 95 and 100 are suitably located to mesh with gears 66 on the outer ends of winding arbors 48 as said arbors are moved successively into winding position in the upper and lower spooling mechanisms by successive rotational movements of spider frames 43. Keyed to drum shaft 83 is a spur gear 101 (Figs. 3 and 4), said gear being connected to pull rollers 31 and 32 for the upper and lower spooling mechanisms, respectively, through a gear 102 on an intermediate shaft 103, friction block 104 keyed to shaft 103, pinion 105 freely rotatable on shaft 103 under the adjustable pressure of a disk 106, an idler 107, and pinions 108 and 109, the latter of which are carried by pull rollers 31 and 32 (Figs. 3 and 4).

In machines of the character described above, whenever the winding operation is interrupted for any purpose such, for example, as the replacement of filled winding cores or spools by empty ones, there is a tendency during the rest periods for the material to cling to the rollers and drums which guide said material through the machine. This condition is especially noticeable in cases where the material is coated with adhesive and the tacky surfaces are permitted to come to rest in contact with said rollers and drums. In consequence it is readily seen that to break down this bonding tendency between the material and the rotary members over which it passes calls for the application of considerable power for this purpose alone. For the purpose of applying additional power for breaking this bonding or clinging tendency after each stoppage of the machine, the present invention contemplates means of suitable construction which operate automatically to increase the application of power whenever the winding operation is initiated and to reduce the application of power to a running normal when the material is running freely through the machine. For this purpose, a cam-operating treadle 110 shown at the left in Fig. 7 to be normally held in elevated position by a yieldable hanger 111, is connected by an inclined link 112 to one arm of a bellcrank 113, the other arm of said bellcrank being connected by a link rod 114 to one arm of a second bellcrank 115. Extending upwardly from the other arm of the second bellcrank is a rod 116 which is connected at its upper end to the outer end of a cam actuating arm 117. As shown in Fig. 3, the arm 117 when depressed imparts an angular displacement to a cam member 118 and a consequent axial displacement to a complementary cam member 119. As shown in Fig. 6, the outward displacement of cam member 119 compresses a spring 120 and thereby increases the pressure between friction disks 91 and thus provides for momentarily increasing the driving power delivered to the gear 92 whenever the treadle 110 is depressed for delivering more power to the driving gear 95 for the upper spooling mechanism. As the machine accelerates, gear 90 moves in a direction counter to the angular displacement of cam 118 and operates thereon by friction to return it to its normal position and thus permits the spooling operation to continue under normal power. A similar increase in the driving power of the pinion 100 for the lower spooling mechanism, may be provided for as follows. A radial arm 121 on cam member 118 is connected by a rod 122 to a radial arm 123 on a cam member 124 of the lower spooling mechanism. Cooperating with cam member 124

is another cam member 125, a relative turning movement between said cam members serving to increase the yieldable pressure applied to friction coupling 97 between spur gears 96 and 98. For the purpose of maintaining oscillatable cam members 119 and 125 in definite rotational relation to each other while at the same time permitting them to be displaced axially to a limited extent, a rod 126 is mounted in side frame 34 (Fig. 3), a perforated connection plate 127 being mounted on the outer end of said rod with a limited amount of lateral play. An arm 128 projects radially from clutch member 119 and is pivotally connected at its outer end to plate 127 through one of the perforations at a distance from one end of a connecting rod 129 which is connected thereto through another perforation. The other end of rod 129 is pivotally connected to the outer end of a radial arm 130 carried by cam member 125.

The starting and acceleration controls are shown in Figs. 1, 7, 8 and 9. Pivotally mounted on a pin 131 at the bottom of the front end of side frame 33 is a rock bar 132 to which is connected a spring 133 which tends to retain the rock bar in one or the other of two extreme positions assumed by said bar at different times. Projecting normally from the rock bar is an arm 134 which is provided with an inclined upper edge 135 for temporarily preventing the downward movement of power treadle 81 until after cam-controlling treadle 110 has been depressed to increase the power transmitted to the spooling mechanisms in the manner described above. A stop pin 136 which projects forwardly from the side frame 33 in the angle between the left-hand arm of rock bar 132 and stop arm 134 is arranged to limit the movement of said rock bar in either a clockwise or counterclockwise direction. Secured to the inner wall of side frame 33 is a bracket 137 with a stop or lug 138 for limiting the upward movement of treadle 81, said bracket being further provided with a downwardly inclined shoulder 139 for retaining treadle 81 in depressed position while the machine is running. While the machine is at rest, the cam and power controls are in their relative positions shown in Fig. 7, the downward movement of power treadle 81 being blocked by stop arm 134 which is then in its extreme position toward the right. To start the machine after installing empty spool assemblies to replace the filled spool assemblies, treadle 110 is depressed to increase the power-transmitting capacity of friction couplings 91 and 97 through which the spooling mechanisms are driven while at the same time removing stop arm 134 from the downward path of treadle 81. As indicated in Figs. 8 and 9, the downward movement of power-controlling treadle 81 moves rock bar 132 in a clockwise direction until the tension of spring 133 becomes active to the right of pivot 131 when said rock bar is actuated thereby to come into engagement with stop pin 136. After treadle 81 has been sufficiently depressed to be anchored below shoulder 139 where it remains until the spooling operation has been completed, treadle 110 is permitted to reassume its upper position to permit the winding operation to continue at normal running speed. The relative positions of the parts while the machine is running is shown in Fig. 9. As soon as the spooling operation has been completed, a slight downward and lateral displacement of treadle 81 serves to release it from the shoulder 139. As the treadle moves upwardly to its initial position shown in Fig. 7 it imparts a slight counterclockwise move-

ment to stop arm 134 which is immediately returned to its initial position (Fig. 7) by the spring 133.

I claim:

5. 1. In a spooling machine for tapes and like articles, the combination with means for guiding the tapes through the machine for delivery to the spooling mechanism, means for starting the machine, spooling mechanism for said tapes, and means operating through the spooling mechanism for applying additional power only during the acceleration of said machine from rest.

10. 2. In a machine for spooling tapes and the like, the combination with a power drive for the machine, spooling mechanism for the tapes, power-transmitting connections between said power drive and said spooling mechanism, means for controlling the transmission of power from said power drive to said machine, and means under the control of the power-controlling means for increasing the power-transmitting capacity of said power-transmitting connections, only during acceleration of said machine from rest.

15. 3. In a machine of the character described, spooling mechanism, means for supplying power to said machine and spooling mechanism, means for starting and stopping said machine, and means under the control of said starting and stopping means for supplying additional power to the spooling mechanism only during the acceleration of said machine from rest.

20. 4. In a winding device in which a winding arbor for winding flexible material is alternately started and stopped at intervals, the combination with a slip friction clutch for driving said arbor, of cam means and connections to said clutch adjustable when the clutch is at rest to increase the frictional contact of the elements of said clutch, said cam means being automatically operated through said connections by angular displacement of said clutch regardless of speed to automatically decrease the frictional contact of said elements.

ROBERT McC. JOHNSTONE.
